UNITED STATES PATENT OFFICE.

HARRY C. FERGUSON, OF CANTON, OHIO, ASSIGNOR TO WYCKOFF, SEAMANS & BENEDICT, OF ILION, NEW YORK, A CORPORATION OF NEW YORK.

TYPE-WRITING MACHINE.

No. 904,858.

Specification of Letters Patent.

Patented Nov. 24, 1908.

Application filed September 27, 1906. Serial No. 336,512.

To all whom it may concern:

Be it known that I, HARRY C. FERGUSON, a citizen of the United States, residing at Canton, in the county of Stark and State of Ohio, have invented certain new and useful 5 Improvements in Type-Writing Machines, of which the following is a specification.

The present invention relates to typewriting machines and more particularly to 10 means for readily producing what may be termed "liner" work, that is to say, to means for producing leader or following-lines in invoice or indexes or for producing lines of stars or underscoring and the like.

15 To the above and other ends which will hereinafter appear, my invention consists of the features of construction, arrangements of parts and combinations of devices to be set forth in the following specification and 20 particularly pointed out in the appended claims.

In the accompanying drawings, wherein like reference characters designate corresponding parts in the various views, Figure 25 1 is a perspective view as seen from the rear showing one form of typewriting machine embodying my invention. Fig. 2 is a detail top view of the actuating rack or bar and some of the associated parts. Fig. 3 is a detail 30 tail side elevation partly in section showing the "liner" type bar and part of the mechanism designed to actuate it. Fig. 4 is a detail perspective view of the type bar actuating wheel and some of the associated parts. Fig. 35 5 is a sectional view of the connecting pawl and its support. Fig. 6 is an enlarged fragmentary detail perspective view showing a portion of the type actuating wheel and some of the associated parts.

40 The present invention relates to another construction employed for the same general purposes as the construction of my application No. 394,142 in which broader claims are presented, covering the present invention; 45 the claims of this case being limited to features not embodied in said application No. 394,142.

There are various styles or kinds of typewriters. In some machines the paper is applied to a carriage which travels while the printing instrumentalities remain relatively stationary. In other machines the printing instrumentalities are mounted on a traveling carriage while the paper holding devices remain relatively stationary. I have elected

to show my invention carried out in the first mentioned kind of writing machines but I do not wish to be confined or limited to a machine of this description, as my invention may be carried out in any known style or kind of typewriting machines.

In the accompanying drawing, 1 represents the typewriting machine frame which within itself forms no particular part of the present invention but is illustrated conventionally for the purpose of showing the relation of the novel devices of my invention to said frame. Above the top plate of the frame 1 is mounted a carriage 2 which may be of any desired construction and is so 70 mounted that it can be moved back and forth across the top plate in the usual manner. The carriage has a rotary platen which platen with the platen frame and associated parts are not shown in Fig. 1 but are or may 75 be of the usual construction. The platen is diagrammatically illustrated in Fig. 3. To the carriage 2 is attached a toothed bar or rack 3 which moves with the carriage and is for a purpose to be hereinafter described. 80 To the frame 1 of the typewriting machine is securely attached a bracket 4 provided with bearings 5 in which is journaled a shaft 6 having fixedly mounted on the forward end thereof a pinion 7 which meshes with the 85 teeth of the rack 3, the latter rotating said pinion when the carriage is moved in either direction. Upon the shaft 6 is also securely mounted a ratchet wheel 8 and adjacent to said ratchet wheel and loosely mounted on the shaft 6 is a rotary device 9 preferably 90 provided with a series of inclined teeth, cams or actuating faces 10. A type bar 11 of the usual construction is mounted on the frame of the machine and is provided with a type 95 designed to impress upon the paper a series of dashes, dots, stars or underscoring marks. formed either of continuous or broken lines such as are commonly used in preparing bills or indexes and the like, the particular 100 formation of type depending upon the character of the marks to be imprinted. The type bar 11 is designed to be actuated by mechanism operated by the movement of the carriage when the carriage is moved to the 105 right, or to the left, as seen from the rear of the machine as in Fig. 1, the rack bar 3, wheel 9 and intermediate parts above described, being parts of such mechanism.

As a very rapid movement is imparted to 110

the type bar 11 during the return movement of the carriage, it is desirable to effect a preliminary movement of said type bar to partly elevate it before it is actuated by the 5 movement of the carriage through the rack 3. An angular lever 12 is provided for this purpose and to the end of the rearwardly extending lower arm of this lever is connected link 13 which extends downwardly from 10 the lever 12 and is connected at its lower end to the rear arm of a lever 14 pivoted upon a bracket secured to the base of the machine. The lever 14 extends fore and aft of the machine and is pivotally connected at its 15 forward end to an upright link 15 designed to actuate the type bar 11 and connected at its upper end to a crank arm 16 connected with the type bar.

The angular lever 12 is actuated by a pin 20 18 carried upon a plate 17 which is adjustably secured to the rack 3 by a screw and slot connection, the connection affording an adjustment of the plate and pin lengthwise of the rack. This pin is adapted, during the 25 first part of the travel of the carriage to the right, to contact with the upper end of the upright arm of the angular lever 12 as shown in Fig. 1 in order to actuate said angular lever to move it to operative position. 30 The effect of this movement of the angular lever is to elevate the link 13, thereby turning the lever 14 against the tension of its spring 36, thus moving the link 15 down to the full line position shown in Fig. 3 in 35 order to effect a preliminary movement of the type bar to bring it adjacent to the printing position as shown in Fig. 3. In order to hold the angular lever 12 in the position to which it is set by the pin 18 a locking device 40 or arm 20 is provided, said locking device being pivoted to a bracket 21 secured to the top plate of the machine. The free end of the locking arm is normally pressed towards the rear of the machine and to the right by 45 a spring 23 which co-operates therewith and forces the locking arm into a notch 22 formed in the upright arm of the angular lever so that the angular lever is locked in its actuated position against movement to 50 the normal position. The construction and arrangement of the parts is such that the locking arm will move into the notch 22 after the angular lever has been moved to the operative position by the pin 18 at or about the 55 beginning of the return movement of the carriage from left to right. When the teeth of the rack 3 come into mesh with the pinion 7 during the movement of the carriage to the right a rotary movement will be imparted to 60 the shaft 6 and this rotary movement of the shaft 6 is transmitted to the actuating wheel 9 by means of the ratchet wheel 8 and a pawl 19, the latter being carried by the actuating wheel and pressed by a spring 28 into engagement with the teeth of the ratchet wheel 65

as shown in Fig. 4. The construction is such that the wheel 9 is turned by the carriage in one direction but not in the other.

The rotation of the actuating wheel 9 imparts a vibratory movement to a lever 2 70 pivotally supported between its ends upon an arm or lug 25 which forms part of the bracket 4. The lower end of the lever 24 is pivotally connected to a horizontally disposed link 26 provided with an eye at its 75 forward end through which the link 15 freely passes. By this arrangement a rotation of the actuating or cam wheel 9 is effective to intermittently move the upper end of the lever 24 rearwardly and allow it to spring 80 back, thus imparting a vibratory movement to the link 26 fore and aft of the machine, the link 26 being supported near its forward end in a fixed guide carried by the bracket 4, said guide being in the nature of a depending wire with a loop formed at the lower end thereof and through which the link 26 passes. The fore and aft vibration of the link 26 is effective to swing the upper end of the link 15 transversely from the full to the 85 dotted line position shown in Fig. 3, thus moving the type bar 11 from the position shown in full lines to the printing position indicated in dotted lines in said figure. It 90 should be understood that this rotary movement transmitted through the pawl and ratchet to the actuating wheel 9 is effected during the return movement of the carriage or during its movement from left to right. During the feed movement of the carriage 100 from right to left the pinion 7 will be rotated but the pawl or detent 19 in this instance will ride over the teeth of the ratchet wheel and no rotary movement will be imparted to the actuating wheel 9 so that the type bar 105 will remain at rest at this time.

In case the typewriting machine is to be used in the ordinary manner and it is desired to throw the line printing type out of operation, it is merely necessary to move the pawl 110 19 axially on the boss 29 on which it is pivoted and against the pressure of a spring 33 (Fig. 5). This movement is effective to throw the detent out of co-operation with the ratchet teeth of the wheel 8 and it may at 115 this time be allowed to rest upon the periphery of the disk 27 as shown in Fig. 6, which disk is adjacent to and may be formed on the forward face of the ratchet wheel. This results in throwing the actuating wheel 9 out of operation during the movement of the carriage in both directions so that no motion will at this time be transmitted to the type bar 11 and it is rendered inoperative. In 120 order that the pawl 19 may be held in either of its adjusted positions, that is to say, where it co-operates with the teeth of the ratchet wheel or rests on the periphery 27 of the disk, the boss 29 on which the detent is pivoted is preferably formed integral with the 125 130

nut 30 and this nut is threaded upon a spindle or post 32 secured to the actuating wheel 9. By rotating the nut 30 in one direction it will be moved toward the head 31 formed on the post, thereby moving the pawl 19 axially against the tension of the spring 33 and towards the periphery 27 of the disk and away from the teeth of the ratchet wheel. When it is desired to bring the pawl into proper engagement with the ratchet wheel 8 the engaging end of the pawl is elevated by pressure exerted on the tail or end 34 of the pawl and the nut 30 is rotated in a direction to move it away from the head 31, at which time the spring 33 forces the pawl toward the actuating wheel 19 and into a position where the engaging end of the pawl may engage the teeth of the ratchet wheel.

In order to release the angular lever 12 from locked position automatically as the carriage approaches the end of its movement to the right, a block, contact or cam 34^a is provided on the rack 3 and may be adjustably secured thereto by a screw and slot connection in order to afford an adjustment of the cam in the direction of the length of the rack 3. During the travel of the carriage to the right the cam 34^a is adapted to contact with a lip 35 formed on the locking arm 20 in order to move the free end of the locking arm towards the front of the machine, thus releasing it from engagement in the notch 22 in the angular lever and the lever is thus automatically released and it, together with the parts associated therewith, may be moved to normal position by the restoring spring 36.

In order to allow the pin 18 to pass the upright arm of the angular lever 12, in the movement of the pin from a position to the right of the lever, the end of said pin is beveled or formed with a cam face as will be seen from an inspection of Fig. 2. As the carriage travels from right to left the beveled end of the pin is brought into contact with the upright arm of the angular lever, deflecting it laterally toward the rear of the machine to permit the pin to pass. When the pin passes the upright arm the inherent resiliency of the lever arm causes it to swing back towards the front of the machine and into the path of the pin to be actuated thereby during the next movement of the pin to the right.

The operation is as follows: The carriage being, it may be supposed, at the right-hand side of the machine with the paper inserted, the operator proceeds with the writing and the carriage is fed from right to left. During the feed movement of the carriage the rack 3 travels therewith, turning the pinion 7 and the ratchet wheel 8 and at this time the pawl 19 slides freely over the teeth of the ratchet wheel so that no motion is transmitted to the actuating or cam wheel 9 and no movement is transmitted to the type bar

or carrier 11. During this movement of the carriage the upright arm of the lever 12 is deflected rearwardly by the pin 18 to allow said pin to pass and springs back into the path of the pin after it has passed. When 70 the carriage reaches the end of the line the pin 18 is in a position slightly to the left of the upright arm of the bell crank lever 12 and in a position to actuate it. As the carriage starts to return to the right the pin 18 75 turns the lever 12 on its pivot, thus bringing about a movement of the link 13, lever 14 and link 15 to effect a movement of the type bar 11 to the full line position in Fig. 3 where the type bar is adjacent to the printing position. The parts are automatically locked in this position by the locking device or arm 20 engaging the notch 22 of the angular lever 12. During the movement of the carriage to the right a rotation is transmitted to the pinion 7 through the rack 3. The effect of this rotation of the pinion 7 is to turn the actuating wheel 9 through the engagement of the pawl 19 with the ratchet wheel 8. The rotation of the actuating or 90 cam wheel 9 is effective to vibrate the lever 24, and links 26 and 15 to intermittently vibrate the type bar 11 from the full to the dotted line position shown in Fig. 3, it being understood that an actuation of the 95 type bar 11 is effected at regular intervals in the movement of the carriage, and an imprint will be effected for each printing movement of the bar. When the cam 34^a reaches the projection 35 the locking arm 20. 100 will be turned on its pivot, releasing the lever 12 and said lever and the parts controlled thereby will be restored to their normal positions. By adjusting the pin 18 and the cam 34^a, the points, with reference to the 105 travel of the carriage where the lever 12 and the parts controlled thereby are automatically actuated and released from their locked positions, may be nicely determined.

Various changes may be made without departing from the spirit of my invention, said invention contemplating as it does broadly the provision of a rotary device controlled by the movement of the carriage for transmitting printing movements to a 115 type carrier. While I have referred herein to the movement of the carriage from left to right and the action of the parts under such conditions it will be understood of course that in other styles of machines the 120 action of the parts may be varied in accordance with the style of machine to which the devices of my invention are applied.

What I claim as new and desire to secure by Letters Patent, is:—

1. In a typewriting machine, the combination of a carriage, a rack, a rotary device actuated by said rack and controlled by the movement of the carriage, a type carrier actuated by said rotary device, and means 130

intermediate the rack and rotary device for rendering the rotary device inoperative to move the type carrier to the printing point.

2. In a typewriting machine, the combination of a carriage, a rotary actuating device, intermediate means between said rotary device and the carriage for causing the rotary device to be actuated by the movement of the carriage in one direction and to afford 10 a movement of the carriage in the other direction without rotating said rotary device, and a type carrier actuated by said rotary actuating device.

3. In a typewriting machine, the combination of a carriage, a rotary actuating device, intermediate means between said rotary device and the carriage for causing the rotary device to be actuated by the movement of the carriage in one direction and to afford a 20 movement of the carriage in the other direction without rotating said rotary device, a type carrier actuated by said rotary actuating device, and means for rendering said intermediate means inoperative to rotate said 25 rotary device.

4. In a typewriting machine, the combination of a carriage, a rotary actuating device, a type carrier actuated by said rotary actuating device, and pawl and ratchet mechanism 30 intermediate said carriage and the rotary actuating device.

5. In a typewriting machine, the combination of a carriage, a rotary actuating device, a type carrier actuated by said actuating device, pawl and ratchet mechanism intermediate 35 said carriage and the rotary actuating device, and means for rendering the pawl inoperative on its ratchet.

6. In a typewriting machine, the combination of a carriage, a vibratory type carrier, preliminary moving means for moving said type carrier adjacent to the printing position, an automatically actuated rotary device controlled by the travel of the carriage for 45 moving said type carrier to the printing position from the position to which it is moved, by said preliminary moving means, and means shiftable to different set positions for rendering and maintaining indefinitely the 50 carriage inoperative on said rotary device.

7. In a typewriting machine, the combination of a carriage, a type carrier, preliminary moving means for moving said type carrier adjacent to the printing position, means for 55 automatically locking the preliminary moving means in the actuated position and for

automatically releasing the same, and an automatically actuated rotary device controlled by the movement of the carriage for moving said type carrier to the printing position from the position to which it is moved by said preliminary moving means. 60

8. In a typewriting machine, the combination of a typewriter frame, a carriage, a toothed bar carried by the carriage, a shaft, 65 a pinion adapted to be rotated by the longitudinal movement of the carriage, said pinion being mounted upon said shaft and meshing with said toothed bar, a toothed wheel mounted upon the shaft, a lever actuated by 70 said toothed wheel, a link pivoted to said lever, a second link actuated by the first mentioned link, and a type bar actuated by said second link.

9. In a typewriting machine, the combination of a frame, a carriage slidably mounted thereon, a type bar, a type bar actuating lever actuated by the movement of the carriage, connections between said lever and type bar, and operative connections between 80 the carriage and said lever which comprise a toothed bar, a pinion adapted to mesh with the toothed bar, and means intermediate the pinion and lever, whereby the type bar is actuated by the movement of the carriage. 85

10. In a typewriting machine, the combination of a frame, a carriage slidably mounted thereon, a type carrier, a shaft, an actuating wheel loosely mounted upon said shaft, means for rotating the shaft by the movement of the carriage, means for operatively connecting the actuating wheel with said shaft, and means operated by said actuating wheel for actuating said type carrier. 90

11. In a typewriting machine, the combination of a frame, and a carriage slidably mounted thereon, a toothed bar carried by the carriage, a rotatable shaft provided with a fixed pinion and a loosely mounted toothed wheel, a lever adapted to be actuated by the 100 rotation of the toothed wheel, links located between the lever and type bar whereby the type bar is actuated by the movement of said lever, and means for rotating the toothed wheel with the shaft. 105

In testimony that I claim the above, I have hereunto subscribed my name in the presence of two witnesses.

HARRY C. FERGUSON.
